UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

AUTOMATIC VOLUME CONTROL

Application filed March 30, 1929. Serial No. 351,410.

The present invention relates to volume control systems, and, more particularly, to a method of, and means for, automatically controlling the amplification volume of a receiving circuit.

Historically, the first receiver to show self-governing characteristics, with reference to its amplification volume, was the resistance coupled radio frequency amplifier employing high resistance values of grid leak. In this amplifier, the radio frequency amplification decreased as signal input increased, due to the increasing negative bias on the amplifier tubes. It will be observed that in this method the maximum wave amplitude is what determines the radio frequency amplification.

Now, I have discovered a system for automatically controlling the amount of amplification in a receiving circuit, the system utilizing the strength of a carrier wave, rather than the maximum wave amplitude, whereby the radio frequency amplification is not varied by audio frequency variations of the incoming wave amplitude, which would reduce the effectiveness of the modulation, but is varied only by variation of carrier wave amplitude, which may be due to general fading effects, or to tuning in of different stations.

Accordingly, it is one of the main objects of my present invention to provide an automatic volume control system in a receiving circuit, which system compensates for fading, equalizes local and distance stations and effectively prevents the occurrence of loud blasts when a strong local station is unexpectedly tuned in, the system including the amplification of the steady direct current component of a detector plate current that corresponds to the rectified carrier alone, and the utilization of the amplified direct current to control the radio frequency amplification of the circuit.

Another important object of the invention is to provide automatic volume control in a receiving circuit, the strength of the carrier wave controlling the amount of amplification in the circuit, the volume control mechanism comprising a magnetron direct current amplifier adapted to amplify the recti-

fied output of a receiving circuit, and means for impressing the output of the amplifier on the radio frequency amplifying stages of the receiving circuit.

Another object of the invention is to provide automatic volume control in a receiving circuit, the control mechanism comprising means for supplying biasing potential to the radio frequency amplifying stage or stages of the circuit, the last named means including an oscillator, the oscillation strength of which is controlled by variations in the carrier potential on a detector preceding the oscillator.

The inventive features for the accomplishment of these and other objects are shown herein in connection with an improved automatic volume control system which, briefly stated, includes the amplification of the steady direct current component of the detector plate current that corresponds to the rectified carrier wave current alone.

By this means a negative potential may be obtained that changes many volts when the carrier voltage on the detector changes a fraction of a volt. This change of negative potential may be applied to the grid return of one or more amplifier tubes, preferably radio frequency stages, the adjustment being such that if the detector input is less than a certain voltage m , the set operates with a maximum amplification, but if the detector input increases to an amount " e ", the amplification would be reduced to zero. Thus, the detector input cannot exceed " E " volts, and $e-m$ may be made as small as desired by sufficient of the direct current amplification mentioned above.

The novel features which I believe to be characteristic of my invention are set forth in particularity in the appended claims, the invention itself, however, as to both its organization and method of operation will best be understood by reference to the following description taken in connection with the drawings in which I have indicated diagrammatically several circuit organizations whereby my invention may be carried into effect.

In the drawings,

Figure 1 shows diagrammatically a receiving circuit embodying the automatic volume control mechanism of my invention,

5 Figure 2 shows a magnetron amplifier circuit adapted to be used in place of the direct current amplifier shown in the receiving circuit in Figure 1,

10 Figure 3 shows a form of magnetron amplifier circuit slightly modified from that shown in Figure 2,

Figure 4 shows diagrammatically a receiving circuit, embodying another modification of a magnetron.

15 Figure 5 shows still another modified form of volume control, embodying a magnetron,

Figure 6 shows diagrammatically a receiving circuit in which automatic volume control is secured by still another modification.

20 Referring to the accompanying drawings, in which like characters or reference indicate the same parts in different views, Figure 1 shows a receiving circuit which embodies an automatic volume control mechanism coupled to a detector tube 3, the input circuit of the tube 3 being tuned, in the well known manner; there being the usual grid condenser, shunted by a leak resistance, interposed in the grid circuit of the tube, although the grid bias type or any type of detection may be used.

25 The input circuit of the tube 3 is coupled, as at M_3 , to the output circuit of a radio frequency amplifier stage 2, the plate circuit of the tube 2 being energized by a source "B", and the input circuit of the tube being tuned, as is well known in the art. The input circuit of the tube 2 is coupled, as at M_2 , to the output circuit of the first radio frequency amplifier stage 1, the input circuit of tube 1 being tuned, and the plate circuit of the tube being energized by a source "B". An antenna circuit W grounded as at G , is coupled as at M_1 , to the input circuit of the tube 1. The filaments of the tubes 1, 2 and 3 are grounded.

30 Across the output circuit of the tube 3 there is connected a capacity C in series with the primary coil of an audio transformer 4, the coil being connected to the filament end of the circuit and the capacity to the plate. The secondary coil of the transformer 4 is connected, in the usual manner, to any type of well known utilization means, such as phones, loud speaker or an additional audio frequency amplifier.

35 In series with the plate of tube 3 there are arranged successive choke-coils L , L_1 , L_2 , capacities C_1 , C_2 , being connected across the output circuit of tube 3, it being noted that the choke coils and capacities C_1 , C_2 , form a low-pass filter permitting only the steady direct current component of the plate current of the detector 3 to flow through a high resistance R connected in series with a source 40 of plate potential "B", both resistance and

source being connected in series with the choke coils.

It should be noted that the steady direct current component of the detector plate current corresponds to the rectified carrier alone, and by means of the resistance R a negative potential may be obtained that changes several volts when the carrier voltage on the detector 3 changes a fraction of a volt. As stated above, between points A, B of the output circuit of the detector 3, a high resistance R is inserted to obtain voltage input for a simple direct current amplifier.

45 This amplifier includes a tube 6, the grid of which is connected by an adjustable means 5 to the source "B", and the plate circuit of which is energized by a source "B". A second high resistance R_1 is connected in series with the plate of tube 6, and potential is adjustably secured therefrom by a variable 50 member 7, the latter being connected by a line 8 to the input circuits of each of the radio frequency amplifier stages.

55 The receiving circuit, as shown, is operated in the usual manner, the input stages of the tubes 1, 2 and 3 preferably being uni-controlled, and the audio current being continuously utilized through the audio frequency transformer 4. The direct current due to the carrier wave, is employed for automatically controlling the amount of amplification secured in the radio frequency amplifier stages. The operation of the volume control mechanism will be apparent from the drawing and description as given.

60 It is to be understood that the circuit elements are so adjusted that if the detector input is less than a certain voltage m , the set operates with a maximum amplification, but if the detector input is increased to an amount e , the amplification would be reduced to zero. Thus, if the signals are strong enough to be brought up to value m by maximum amplification, the detector input cannot vary by more than $e-m$ volts, and, of course, this variation may be made as small as desired by sufficient of the direct current amplification.

65 When strong signals are received the direct current in the plate circuit of the detector 3 is decreased. As a result of this the output of the direct current amplifier 6 is increased causing an increased current flow through resistance R_1 . The increased current flow through resistance R_1 causes the point A thereon to become relatively more negative, and from this there follows an increased negative bias on the grids of amplifiers 1 and 2 which in turn cuts down their amplification.

70 Conversely, when the incoming signal energy diminishes in value then the current flowing through the resistance R_1 decreases and the grid bias on tubes 1 and 2 becomes less negative. By virtue of the latter fact the amplification of tubes 1 and 2 of the in-

coming signal increases, and, hence, in the utilization means there is maintained a signal of substantially constant intensity.

In other words, it will be seen that I have devised a method for maintaining signal amplification between predetermined limits of intensity, which system involves the amplification of small variations in the direct current component of the plate current of the detector of a receiving circuit; which variations are engendered by corresponding variations in the strength of the incoming carrier wave, the amplified variations being adjusted to control the radio frequency amplifying stages of the receiving circuit by biasing the grid of each amplifying stage in such a manner that the amplifying stages operate within the predetermined limits.

Instead of the direct current amplifier shown in Figure 1 a direct current amplifier, employing magnetrons, may be utilized as shown in Figure 2. Between points A and B of the receiving circuit shown in Figure 1, the circuit members preceding these two points being omitted for the sake of simplicity, the magnetron field coil 11 is connected. The source "B" is used to adjust the field coil 11 to its critical value by means of an adjustment member 11'. The magnetron diode 9 has its plate energized by a source "B", and a second field coil 12 is connected in series with the source "B".

The latter coil 12 controls the action of a second magnetron 10, the output current of this final magnetron flowing through a resistance R_1 arranged in its plate circuit, the control voltage being taken off by an adjustable member 7 from the resistance R_1 . As in Figure 1, the potential from the resistance R_1 is led through a line 8 to the grids of the amplifying stages of the receiving circuit.

In Figure 3 there is shown a magnetron amplifier, modified from the amplifier shown in Figure 2, in that, instead of using the source "B" for adjusting the field coil 11 to its critical value, another field coil 13, connected in series with a rheostat 15 and a source of potential 14, adjusts the field to its critical value. The amplifier in Figure 3 functions in the receiving circuit in the same manner as described heretofore.

In Figure 4, there is shown a receiving circuit of the same type shown in Figure 1, employing a magnetron amplifier in which a magnetron field coil 16 is connected between points A, B, the critical value of the field coil being adjusted by a second field coil 18 connected in series with a rheostat 19 and a source of potential 20, as noted in Figure 3. The magnetron diode 17 has connected in series with its plate circuit a resistance R_1 in series with a source "B" of potential for the diode plate.

The magnetron amplifier output is impressed upon the plate circuits of the am-

plifier stages 1, 2 by means of connecting lines 23, 24. It will be observed, that in this type of circuit, a change of plate resistance R_1 of the magnetron 17 affects the plate voltage of the radio frequency amplifiers 1, 2. 70

When the magnetron resistance falls from nearly infinity to nearly zero, the plate voltages of the tubes 1, 2 drop from approximately the value of the potential of source "B" to nearly zero. If the operating point is at the knee of a sharp-cut off magnetron the reduction of the plate potential would be very rapid.

When only a single magnetron is used, volume may be determined by the adjuster 19 of the field. If this is brought away from the critical value no control would be effected. If brought onto the steep part of the curve, the amplification would be reduced even for weak signals, and the governing action will be "stiffest". 80

Another modification of a receiving circuit employing a magnetron amplifier for automatic volume control, is shown in Figure 5. In this circuit, the circuit elements are the same as in Figure 1, but a magnetron field coil 30 is connected between points A, B, a magnetron diode 29 having a source "B" in its plate circuit, the negative terminal of the source being connected to the filament of amplifier stage 25 by a line 21, the other terminal of the diode 29 being connected by a line 32 in the plate circuit of the tube 25. 90

As in Figure 1, the audio current from the detector is utilized in any well known form of utilization means, and the direct current passed through a low-pass filter. The critical value of the field coil 30 is controlled by a second field coil 28 having connected in series therewith a rheostat 26 and source 27, as shown in Figure 3. In this case magnetron 29 varies the amplification of tube 25 by interposing in the plate circuit a resistance, which varies from a negligibly small value 110 up to infinity according to the current in field coil 30.

Another interesting modification of the circuit shown herein is the utilization of the potential drop across the resistance R connected between points A, B for determining the output of an oscillation generating arrangement, which output being rectified and smoothed out provides potential for the grids of the radio frequency amplifier stages of the circuit. The output of a master oscillator is impressed upon the grid circuit of the tube 33 through a coupling M_4 , the grid circuit being connected to one end of the resistance R . 115

The plate of tube 33 is energized by a source "B" and is connected to the other end of the resistance R . The plate circuit of the tube 33 is coupled through a resonant circuit 34 to a crystal rectifier 35, the rectified output being filtered through a filter member 120

130

L_3 , C_3 , C_4 there being a resistance R_1 connected across the filter member, whereby after amplification and rectification the oscillations are impressed upon the grid circuit of the radio frequency amplifier stages through lines 36 and 37. In this way the amplification of signal energy is maintained between predetermined limits.

10 While I have indicated and described several systems for carrying my invention into effect, it will be apparent to one skilled in the art that my invention is by no means limited to the particular organization shown and described, but that many more modifications 15 in the circuit arrangements, as well as in the apparatus employed, may be used without departing from the scope of my invention as set forth in the appended claims.

What I claim is:

- 20 1. An automatic volume control for a receiving circuit comprising means for collecting signal energy, signal energy amplifying means, a detector coupled to said amplifying means, a source of detector anode current, 25 a magnetron direct current amplifier including a field coil connected to said source to amplify the direct current component of the detector signal plate current, and means for impressing the output of the magnetron amplifier on the signal energy amplifying means.

30 2. An automatic volume control for a receiving circuit comprising means for collecting signal energy, radio frequency amplifying means, a detecting tube, a source of 35 detector anode current, a magnetron amplifier including a field coil connected to said source to amplify the direct current component of the detector signal plate current, means for adjusting the field coil to its critical 40 value and means, including a resistance, for impressing the output of the magnetron amplifier on the radio frequency amplifying means.

45 3. In combination, in a radio receiver, an antenna, a radio frequency amplifier, a detector stage including an electron discharge tube, an audio frequency transformer primary in the anode circuit of the tube, a direct current blocking condenser connected 50 between the primary and the detector anode, a source of current for said anode, a path of high impedance to pulsating current connected between said anode and the positive side of said source, a high impedance connected between said source and the low potential side of said primary, a direct current 55 amplifier connected across said impedance, and means for controlling the gain of the radio frequency amplifier with the output of said direct current amplifier.

60 4. In combination, in a radio receiver, an antenna, a multi-stage radio frequency amplifier, a detector stage including an electron discharge tube, an audio frequency trans- 65 former primary in the anode circuit of the

tube, a direct current blocking condenser connected in series between the primary and the detector anode, a source of current for said anode, a path of high impedance to pulsating current connected between said anode and the positive side of said source, a high impedance connected between said source and the low potential side of said primary, a direct current amplifier connected across said impedance, and means for controlling the gain of the radio frequency amplifier with the output of said direct current amplifier.

5. In combination, in a radio receiver, an antenna, a radio frequency amplifier, a detector stage including an electron discharge tube, an audio frequency transformer primary in the anode circuit of the tube, a direct current blocking condenser connected between the primary and the detector anode, a source of current for said anode, a path of high impedance to pulsating current connected in series between said anode and the positive side of said source, a high impedance connected in series between said source and the low potential side of said primary, a direct current amplifier connected across said impedance, and means for controlling the gain of the radio frequency amplifier with the output of said direct current amplifier.

6. In combination, in a radio receiver, an antenna, a radio frequency amplifier, a detector stage including an electron discharge tube, an audio frequency transformer primary in the anode circuit of the tube, a direct current blocking condenser connected between the primary and the detector anode, a source of current for said anode, a path of high impedance to pulsating current connected between said anode and the positive side of said source, a high impedance connected between the negative side of said source and the low potential side of said primary, a direct current amplifier connected across said impedance, and means for controlling the gain of the radio frequency amplifier with the output of said direct current amplifier.

7. In combination, in a radio receiver, an antenna, a multi-stage radio frequency amplifier, a detector stage including an electron discharge tube, an audio frequency transformer primary in the anode circuit of the tube, a direct current blocking condenser connected in series between the primary and the detector anode, a source of current for said anode, a path of high impedance to pulsating current connected in series between said anode and the positive side of said source, a high impedance connected in series between the negative side of said source and the low potential side of said primary, a direct current amplifier connected across said impedance and means for controlling the gain of the radio frequency amplifier with the output of said direct current amplifier.

quency amplifier with the output of said direct current amplifier.

15. In a radio receiver, a radio frequency amplifier stage including a tube, a detector stage including a tube, a source of direct current for the detector tube anode, means in the detector anode circuit for coupling the same to an audio frequency signal utilization means, means for amplifying the direct current output of the detector tube comprising a magnetron diode, a field coil for the diode connected to the said current source in the detector anode circuit, and a gain control connection between said diode and a cold electrode of the radio frequency amplifier tube.

16. In a radio receiver, a radio frequency amplifier stage including a tube, a detector stage including a tube, a source of direct current for the detector tube anode, means in the detector anode circuit for coupling the same to an audio frequency signal utilization means, means for amplifying the direct current output of the detector tube comprising a magnetron diode, a field coil for the diode connected to the said current source in the detector anode circuit, and a gain control connection between said diode and a positive cold electrode of the radio frequency amplifier tube.

30 17. In a radio receiver, a radio frequency amplifier stage including a tube, a detector stage including a tube, a source of direct current for the detector tube anode, means in the detector anode circuit for coupling the same to an audio frequency signal utilization means, means for amplifying the direct current output of the detector tube comprising a magnetron diode, a field coil for the diode connected to the said current source in the detector anode circuit, said diode being connected in series in a cold electrode circuit of said amplifier tube to provide a gain control circuit.

45 18. In a radio receiver, a radio frequency amplifier stage including a tube, a detector stage including a tube, a source of direct current for the detector tube anode, means in the detector anode circuit for coupling the same to an audio frequency signal utilization means, means for amplifying the direct current output of the detector tube comprising a magnetron diode, a field coil for the diode connected to the said current source in the detector anode circuit, said diode being connected in series in a positive cold electrode circuit of said amplifier tube to provide a gain control circuit.

60 19. In a radio receiver, a radio frequency amplifier stage including a tube, a detector stage including a tube, a source of direct current for the detector tube anode, means in the detector anode circuit for coupling the same to an audio frequency signal utilization means, means for amplifying the direct current output of the detector tube comprising

a magnetron diode, a field coil for the diode connected to the said current source in the detector anode circuit, and a gain control connection between said diode and the radio frequency amplifier and means for controlling the action of said magnetron diode.

70 20. In a radio receiver of the type comprising a radio frequency amplifier, including a tube, having a resonant input circuit tuned to a desired signal frequency, a detector, including a tube, provided with an input circuit coupled to the amplifier to receive signal energy therefrom to be rectified, and means for utilizing the audio frequency component of rectified signal energy, an automatic volume control arrangement comprising a magnetron diode, a field coil for said diode connected to the said detector and disposed in the path of flow of the direct current component of the rectified signal energy, and a direct current connection between said diode and a cold electrode of said amplifier tube for adjusting the potential of said cold electrode in response to variations of said direct current component flow through said field coil.
